LEAKPROOF CONTAINER FOR FLUIDS

Alphonse J. Kramer, Antioch, Calif.

Application July 1, 1936, Serial No. 88,423

2 Claims. (Cl. 229—33)

This invention relates to folding paper boxes.

It is an object of the invention to provide a paper container, of the type commonly used for ice cream, or products of a like nature, with a closure member which renders the container fluid-tight.

Another object of the invention is to provide a container of the class described with a closure, supplementing the closure for rendering the container fluid-tight, which affords protection of the second closure against puncture or displacement.

Still another object of the invention is to provide an integral portion of the container which functions simultaneously to provide a lock for shutting the closure and a handle by means of which the container may be carried.

The invention possesses other objects and valuable features, some of which, together with the foregoing, will be specifically set forth in the detailed description of the invention hereunto annexed. It is to be understood that the invention is not to be limited to the particular species thereof shown and described herein, as various other embodiments thereof may be employed within the scope of the appended claims.

The broad aspects of the invention may be ascertained by reference to the accompanying drawing, in which:

30 Figure 1 is a front elevational view of a container embodying the principles of the invention. A portion of the view is broken away to more clearly disclose the construction.

35 Figure 2 is a side elevational view of the structure shown in Figure 1.

Figure 3 is a front elevational view of the container showing the outer closure shut.

Figure 4 is a top plan view of the unfolded inner closure member.

40 Figure 5 is a top plan view of the blank from which the container is formed.

It is contemplated to provide a container composed of light fiberboard in which liquids, or other products containing liquids may be safely packed, and which will, due to the very low cost of manufacture, replace costly glass or sheet metal containers now in common use for packaging goods of this character. It is further contemplated, by providing a container, upon which advertising matter may be directly printed, to dispense with the expensive labels used on the glass or sheet metal containers mentioned above.

In detail, and referring particularly to Figure 5, of the drawing, the container is formed from a blank having a rectangular center portion, 6

defined by longitudinal and transverse scores 7 and 8 respectively. Extending from the transverse edges of the center portion are end wall portions 9 having diverging edges 10, and provided with a transverse score 11 beyond which 5 extends a cover flap 12.

Extending from one longitudinal edge of the center portion is a side wall portion 13 bordered by diverging scores 14 and a transverse score 15, and extending beyond the latter score is a cover 10 flap 16 provided with a slot 17. The opposite longitudinal edge of the center portion is provided with a side wall portion 18 extending therefrom, this portion being provided, like the side wall portion 13, with diverging scores 19 and a 15 transverse score 20; and extending beyond the score 20 is a cover flap 21 provided on its outer edge with a tabular projection 22, having therein an aperture 23, and provided at the junction thereof with the flap portions 21, with a notch 20 24. Both of the side wall portions 13 and 18, along the scores 14 and 19 respectively thereof, are provided with wing-like extensions 25, these extensions being separated from the side wall portions 9 by slits 26.

The container is set up by folding the side wall portions 9 upwardly along the scores 8 to substantially vertical position, similarly bending the side wall portions 13 and 18 upwardly to contact the side edges 10 of the portions 9, and bending 30 the wing-like extensions 25 to positions overlying the outer surfaces of the portions 9, as is shown in Figure 2. The contacting portions of the members 9 and the abutting members 25 are now adhesively secured together, sufficient of 35 the adhesive being applied so that all of the joints, particularly the bottom corners 27 of the container, are leak-proof. Closing of the container may be effected, as is shown in Figure 3, by bending the two cover flaps 12 inwardly and 40 downwardly into overlapping relationship, similarly bending the cover flaps 16 and 21 into overlapping relationship overlying the flaps 12, and engaging the tabular projection 22 with the slot 17. It will be noted that the position of the 45 slot is offset with respect to the center of the flap 16 and the extension 22 so that, when the extension is engaged in the slot, the notch 24 of the extension will overlie the surface of the flap, at one end of the slot, and lock the flaps together 50 against easy or accidental separation. It will also be noted in Figure 3, that by bending the extension 22, along the dotted line 28, to a position at right-angles to the flap, the extension affords a handle by means of which the container 55

may be carried, the aperture 23 being provided for the reception of a finger of the carrier's hand, insuring a firm grip.

Means is provided for hermetically sealing the container to render it leak-proof when the former is used in packaging fluids or other goods containing fluids. In Figure 4 is shown a closure member comprising a central portion 29, defined by longitudinal and transverse scores 30, and extending from each edge of the central portion is a marginal flange 31. This closure is formed by bending each of the flanges 31 to positions lying substantially at right-angles to one surface of the center portion 29, and the closure, after the container has been filled with the material to be packed therein, is inserted in the container, as shown in Figure 1, a suitable adhesive being first applied to the outer surface of each of the flanges so that the closure is sealed to the side and end walls of the container. This closure is intended for use only in the packaging of fluids or other products which will spoil by being exposed to the air for extended periods, and the function of the cover flaps of the container proper, when the second closure is used, is in addition to providing the carrying handle referred to above, to afford protection for the second closure against accidental puncture or displacement thereof.

It is contemplated to treat the fiberboard in different manners, depending upon the nature of the product packed therein, to render the container non-absorbent to the fluids of the product. Thus, if the product contains quantities of water, the fiberboard may, either before or after the container is assembled, be coated or impregnated with paraffin, if the contents is oil or oleaginous

material, the coating or impregnating material may be shellac or a mixture of gelatine and glycerine, or it may also be a mixture of carbon disulphide, linseed oil and caoutchouc. For certain products a casein solution may also be used. 5

It will, of course, be understood that the container above described is to be constructed in sizes capable of holding standard measures, and that for the larger sizes of containers it is necessary to increase the thickness of the fiberboard 10 used so as to provide for a maximum of rigidity, and resistance to collapse or crushing.

I claim:

1. In combination, a container comprising a single sheet of material folded to provide a box 15 having a bottom, side walls, an open end, and flaps extending from said side walls and bordering said open end, a closure member for the open end of said box comprising a sheet of material provided with marginal flanges adhesively secured to said 20 side walls, and said flaps being foldable to positions overlying said closure member.

2. In combination, a container comprising a single sheet of material folded to provide a box having a bottom, side walls, an open end, and 25 flaps extending from said side walls and bordering said open end, a closure member for the open end of said box comprising a sheet of material provided with marginal flanges adhesively secured to said side walls, said flaps being foldable to positions overlying said closure member, one of said flaps having a slot therein, and another of said flaps having an extension thereof engaging in said slot and projecting from said container to provide a carrying handle therefor. 30

ALPHONSE J. KRAMER. 35
